L. GINSBERG

PENCIL POINT PROTECTOR

Filed Nov. 1, 1918

Inventor
L. GINSBERG.

By *Alfred J. Randolph Jr.* Attorney

UNITED STATES PATENT OFFICE.

LOUIS GINSBERG, OF MINNEAPOLIS, MINNESOTA,

PENCIL-POINT PROTECTOR.

Application filed November 1, 1918. Serial No. 260,734.

To all whom it may concern:

Be it known that I, LOUIS GINSBERG, a citizen of Russia, residing at Minneapolis, in the county of Hennepin and State of Minnesota, have invented certain new and useful Improvements in Pencil-Point Protectors; and I do hereby declare the following to be a full, clear, and exact description of the invention, such as will enable others skilled in the art to which it appertains to make and use the same.

My invention relates to improvements in means for protecting pencil points.

An important object of this invention is to provide a conical shaped member adapted to be arranged over the forward end portion of a pencil, to permit of the same to be quickly placed over the point of a pencil for protecting the same.

20 A further object of the invention is to provide a pencil point protector which may be positioned to permit of the using of the pencil without the necessity of removing the pencil point protector from the pencil.

25 A further object of the invention is to provide a pencil point protector comprising a member adapted to encircle the forward end portion of a pencil and having an elastic band encircling the same for retaining the protector in contact with the pencil, said elastic band being also adapted to function as a gripping member to facilitate the handling of the pencil.

30 A further object of the invention is to provide a pencil point protector, which is neat, cheap to manufacture and desirable in use.

35 A further object of the invention is to provide a device of the character described which by virtue of its extreme simplicity and cheapness of manufacture may be profitably distributed for advertising purposes and so forth.

40 Other objects and advantages of the invention will be apparent during the course of the following description.

45 In the accompanying drawings forming a part of the specification, in which like numerals are employed to designate like parts throughout the same,

50 Figure 1 is a side elevation of a pencil point protector applied to a pencil, showing the same arranged rearwardly of the pencil point, and

55 Figure 2 is a similar view of my improved

pencil point protector applied to a pencil, showing the same arranged over the point thereof.

In the drawings, wherein for the purpose of illustration is shown the preferred embodiment of my invention, the numeral 5 generically designates a pencil of the usual construction and provided with a longitudinally extending writing element 6. As is usual, in pencils, the forward end portion 60 thereof is tapered to form a conical shaped member 7.

My invention comprises in part, a cylindrical shaped member 8, which in manufacture, may be of a stout paper, or light flexible metal. The forward end portion of the cylindrical shaped member 8 is provided with longitudinally extending cut-out portions 9, thus forming arms 10. An elastic band 11 is adapted to be encircled about 70 the forward end portion of the arms 10 and is glued or otherwise secured thereto. The elastic band 11 serves to normally retain the arms 10 in contact with the lead 6 or the tapered portion 7 of the pencil. The 75 elastic band 11 is also adapted to function as a gripping element adapted for use in writing. As clearly shown in the drawings, the rear end portion of the cylindrical shaped member 8 is provided with longitudinally extending incisions 12, thus forming partly severed transversely curved arms 13. The arms 13 in being partly severed 80 are possessed of some degree of flexibility and are held in contact with the pencil by a second elastic band 14. The elastic band 14 serves to retain the device in the desired 85 position on the pencil.

In the use of my invention, it will be apparent that when it is desired to protect 90 the pencil point, the arms 10 are arranged over the point 6 by pushing the conical shaped member 8 upwardly slightly. When it is desired to expose the point 6 for writing, it is merely necessary to push the conical shaped member rearwardly and thus 95 expose the point 6. As described, in writing with a pencil having my improved pencil point protector arranged thereon, the elastic band 11 serves as a very desirable 100 gripping element.

105 While I have shown and described the preferred embodiment of my invention, it is understood that I may make such minor 110 changes in arrangement and construction of

parts, as will remain within the spirit of the invention and scope of the appended claim.

Having thus described my invention,
5 what I claim is:—

A sleeve to slide on a pencil, said sleeve being slitted longitudinally from one end and having an elastic band of less diameter than said sleeve disposed on and adapted 10 to constrict the portion of the sleeve at said end into protecting relation to the point

of the pencil, said end portion being flexible to conform to the exterior shape of the pencil at said portion under urgency of the band, and said band serving as a grip when 15 the sleeve is in exposing relation to the point.

In testimony whereof I affix my signature in presence of two witnesses:

LOUIS GINSBERG.

Witnesses:

HENRY A. HUBBARD,
AMERY HUBBARD.
